UNITED STATES PATENT OFFICE.

EDWARD MAYNZ, OF BOSTON, MASSACHUSETTS.

DESIGN FOR A LACING-HOOK HEAD.

SPECIFICATION forming part of Design No. 12,467, dated September 13, 1881.

Application filed April 22, 1881. Term of patent 14 years.

To all whom it may concern:

Be it known that I, EDWARD MAYNZ, of Boston, in the county of Suffolk and State of Massachusetts, a citizen of the United States, have invented a certain new and useful Design 5 for Lacing-Hooks, of which the following is a full, clear, and exact description, reference being had to the accompanying drawings, forming a part of this specification, in explaining its 10 nature, in which—

Figure 1 is a perspective view of a lacing-hook of my design. Fig. 2 is a plan view thereof, and Fig. 3 is a vertical section thereof.

My design consists in the head A, having 15 the rounded central portion, a , and the concentric rib a' and the exterior edge, a^2 , which is curved from one edge, a^4 , of the shoulder or upper surface, a^5 , of the neck a^6 to the other edge, a^4 , as represented in the plan in Fig. 2.

It further consists, in connection with the 20 above-described features, in the neck a^6 , which is curved inwardly, the flat seat a^7 , and the prongs a^8 , projecting at right angles from the front end of the seat.

I desire to state that while I show but one 25 concentric rib a' , I may use two or more, if desired.

Having thus fully described my design, I claim and desire to secure by Letters Patent of the United States—

The design embracing the top or head a a' 30 a^2 , the curved neck a^6 , the flat seat a^7 , and the prongs a^8 at right angles to the seat.

EDWD. MAYNZ.
